UNITED STATES PATENT OFFICE.

HENRY BAUTE, OF BENTON HARBOR, MICHIGAN.

SPLIT PULLEY.

SPECIFICATION forming part of Letters Patent No. 402,221, dated April 30, 1889.

Application filed August 13, 1888. Serial No. 282,562. (No model.)

To all whom it may concern:

Be it known that I, HENRY BAUTE, of Benton Harbor, in the county of Berrien and State of Michigan, have invented certain new and useful Improvements in Split Pulleys; and I do hereby declare that the following is a full, clear, and exact description thereof, reference being had to the accompanying drawings, and to the letters of reference marked thereon, which form part of this specification, in which—

Figure 1 is a face view of my improved split pulley. Fig. 2 is a cross-section of the same. Fig. 3 is a vertical sectional view through one of the pulley-sections.

This invention is an improvement in split pulleys; and its objects are to improve the construction of the pulley-sections and to provide improved bushings therefor, whereby the pulley-sections, when united around a shaft, may be properly centered thereon; and to these ends the invention consists in the novel construction and arrangement of parts, hereinafter described and claimed.

Referring to the accompanying drawings by letter, A and B represent the similar but opposite sections of the pulley. Section A has a transverse spoke-bar, C, which connects the opposite ends of its rim-section a, and c is a spoke connecting the central portion of bar C with the central portion of rim-section a. Section B has a similar transverse spoke-bar, D, and spoke d united to its rim-section b, as shown.

In the inner face of spoke-bar C and centrally thereof is formed a rectangular recess, E, and e is a similar but opposite recess in bar D. When the pulley-sections are united, the shaft would pass through the opening formed by said recesses.

F are lugs projecting from the inner face of bar D at the ends of recess e, and f f are shoulders formed in the inner face of bar C at the ends of recess E, which lugs F F engage when the pulley-sections are united. G G are lugs projecting from the inner face of bar C outside of the shoulders f f, and engaging corresponding shoulders or recesses, g g, in the inner face of bar D, as shown. The spoke-bar D is widened between its lugs F and shoulders g, as shown at H H, and bar C is widened between its lugs and shoulders f,

as shown at i i. Through the widened portions of the bars are made transverse openings J J, which coincide when the pulley-sections are brought together, and through these openings pass uniting-rods K K, the outer ends of which are screw-threaded and engaged by nuts k k, which, when the parts are properly adjusted, draw the bars C D toward each other and firmly unite the sections.

L L are similar bushing-blocks inserted in recesses E e before the rods are tightened. The inner faces of these blocks are longitudinally ovaly concaved, and when bound upon a shaft within the sections they will bite the shaft at two diametrically-opposite points. As the arc of the oval concave is much greater than the circumference of any shaft that could be inserted through the opening formed by recesses E e, and the opposite inclination of the extremities of the concave surface would cause the shaft when the blocks are bound thereon to ride up to the exact center of the blocks, (which is the exact center of the pulley on the parting line thereof,) the pulley can be centered exactly on different sizes of shafting; but to do this I employ packing-blocks or sheets M M, which are inserted between the backs of blocks L and the bottoms of their recesses, as shown, and thereby I can adjust the blocks to the exact center of the pulley, and by increasing or lessening the number of packing-blocks M M, I adapt the pulley to fit large or small shafting, as is evident.

The lugs and shoulders on bars C D, when the rods are tightened, engage, as shown, and insure accurate joints of the rim of the pulley, and they also relieve the rods of any lateral strain and prevent the sections being thrown eccentric to each other by the strain of the belt in starting and running, thus serving a very important function, so that the only strain on the rods is that necessary to draw the sections together on the diametrical line of parting. By having but the two points of contact between the two bushing-blocks and the shaft, and these points being diametrically opposite each other, less strain is necessary to firmly bind the pulley to the shaft than where there are four or more points of contact between the bushings and shaft, and there is less liability of the uniting bolts or

rods being unequally strained should the shaft be worn.

One pair of the shoulders and lugs on the spoke-bars might be omitted in some instances, 5 the remaining pair doing the duty of both; but where a very strong pulley is desired both pairs should be employed, as described.

Having described my invention, I claim—

1. In a split pulley, the combination of the opposite sections having transverse spoke-bars C D, provided with engaging-shoulders f and g, and lugs G and E, to prevent displacement of the sections when united, and the uniting-rods and nuts for said sections, 15 substantially as specified.
2. In a split pulley, the combination of the opposite sections having transverse spoke-bars C D, united to the rim-sections near the ends thereof and provided on their meeting 20 faces with engaging-lugs G F and shoulders f g, and having opposite angular recesses in their meeting faces, with the ovaled faced bushing-blocks L in said recesses, and the uniting-rods, substantially as specified.
- 25 3. In a split pulley, the combination of the opposite sections having recesses E e, for the passage of the shaft in their meeting faces, with the bushing-blocks L L in said recesses, having oval concaved faces, and the packing-blocks M M, placed in recesses E e below blocks L, and uniting-rods and nuts, all substantially as described.

4. The combination of the opposite sections having transverse spoke-bars formed with recesses E e in their meeting faces for the 35 passage of the shaft and having engaging-lugs G F and shoulders f g, substantially as described, with the uniting-rods and nuts, and the ovaled concaved faced bushing-blocks L in the recesses of the bars, and the packing-blocks M M therein, substantially as set forth. 40

5. The combination of the opposite pulley-sections having transverse spoke-bars formed with central angular recesses, and with pairs of engaging shoulders and lugs on their meeting faces and widened between said shoulders, and lugs on opposite sides of the central recess, with the oval concave-faced bushing-blocks mounted in said recesses, the packing-blocks therefor, and the uniting-rods passing 45 through openings in the widened portions of the spoke-bars, and tightening-nuts thereon, all constructed and arranged substantially as described. 50

In testimony that I claim the foregoing as 55 my own I affix my signature in presence of two witnesses.

HENRY BAUTE.
